UNITED STATES PATENT OFFICE.

JAMES R. McCUMBER, OF KINGWOOD, WEST VIRGINIA.

ENGINE VALVE.

Application filed December 10, 1924. Serial No. 754,984.

To all whom it may concern:

Be it known that I, JAMES R. McCUMBER, a citizen of the United States, residing at Kingwood, in the county of Preston and State of West Virginia, have invented a new and useful Engine Valve, of which the following is a specification.

This invention relates to engine valves and aims to provide a novel form of valve which will be noiseless in its operation, and one wherein an air-tight connection between the valve and its seat will be insured at all times, eliminating leakage to increase the power of the engine.

An important object of the invention is to provide a valve which will have a plurality of seats, the same being of a construction whereby the explosion caused within the cylinder will act to force the valve closer to its seat to eliminate leakage.

Another object of the invention is the provision of a valve constructed so that carbon deposits on the valve will not in any way act to decrease the efficiency of the valve.

With the foregoing and other objects in view which will appear as the description proceeds, the invention resides in the combination and arrangement of parts and in the details of construction hereinafter described and claimed, it being understood that changes in the precise embodiment of the invention herein disclosed, may be made within the scope of what is claimed, without departing from the spirit of the invention.

Referring to the drawing:

Figure 1 is a fragmental sectional view through the upper portion of an engine cylinder disclosing a valve constructed in accordance with the invention as mounted in the head thereof.

Figure 2 is a longitudinal sectional view taken at right angles to Figure 1.

Figure 3 is a perspective view of the valve forming the essence of the invention.

Referring to the drawing in detail, the reference character 5 indicates an engine cylinder in which the piston 6 operates, the cylinder and piston being of the usual type, and forming no part of the present invention.

The engine head is indicated at 7 and is provided with the usual compartment 8 to accommodate the cooling fluid employed for maintaining the engine in a cooled condition. This head is provided with recessed portions, one of which being shown in the

present drawing, which recessed portions accommodate the valves forming the essence of the invention. As shown by Figure 1 of the drawing, a recessed portion is indicated at 9, the valve operating therein being indicated at 10, the same being hollow so that the force of the explosion usually directed to the under surface of the head will be directed to the interior of the valve to force it to its seat.

The valve is formed with a tapered upper surface indicated at 11 to which the valve stem 12 is secured and as shown, this upper portion 11 is provided with an exhaust port 13 and an intake port 14, the exhaust and intake ports registering with the exhaust and intake ports 15 and 16 respectively, that are formed in the engine head, manifolds 17 being secured to the head for directing the fuel to the engine cylinders and directing the exhaust from the cylinders.

The reference character 18 indicates a peripheral flange which seats at 19 to insure a tight connection at this point, while the upper tapered portion 11 of the valve seats at 20, to further insure a tight connection between the valve and the recessed portion in which it is positioned.

Mounted on the valve stem 12 is a coiled spring indicated at 21 that has its lower end bearing against the head of the cylinder while the opposite end thereof is positioned in the cap 22 that is held against movement on the valve stem by means of the pin 23. At the upper end of the valve stem is an arm indicated at 24 which extends laterally and is engaged by the forked extremity 25 of the rocker arm 26 which is mounted in the usual manner, on the engine head.

Contacting with the outer end of the rocker arm is the usual push rod 27 that moves in vertical planes so that as the rocker arm 26 is moved upwardly, an oscillating movement will be imparted to the valve proper, through the medium of the arm 24.

In order that the rocker arm 26 will be returned to its initial position after it has been moved to operate the valve member, the push rod 27 is provided with a pin 28 that moves in the slot 29 provided in the rocker arm 26.

From the foregoing it will be seen that due to this construction an oscillatory movement will be imparted to the valve to move the intake and exhaust ports thereof alter-

nately into registry with the intake and exhaust ports of the cylinder head to control the passage of fluid and exhaust gases and cause the operation of the engine.

5 I claim:—

In an engine construction, an engine head having a recessed portion and having inlet and exhaust openings formed therein, a valve including a circular body portion, having a peripheral flange, said flange having an inclined upper edge, the lower edge of the

wall of the recessed portion being beveled to receive the inclined upper edge of the flange to provide a fluid-tight connection between the valve and recessed portion in which the valve operates, and means for operating the valve.

In testimony that I claim the foregoing as my own, I have hereto affixed my signature.

JAMES R. McCUMBER.
